UNITED STATES PATENT OFFICE.

DAVID A. WALLACE, OF BATAVIA, NEW YORK.

MALT-DRIER.

SPECIFICATION forming part of Letters Patent No. 360,257, dated March 29, 1887.

Application filed October 14, 1886. Serial No. 216,201. (No model.)

To all whom it may concern:

Be it known that I, DAVID A. WALLACE, of Batavia, in the county of Genesee and State of New York, have invented a new and useful 5 Improvement in Machines for Turning Malt, which improvement is fully set forth in the following specification and shown in the accompanying drawings.

It is well understood that in malting grain 10 the wet germinated kernels are subjected to a thorough drying process in suitably-constructed kilns by the application of furnace heat to the floor thereof, in doing which the grain has to be frequently stirred or turned 15 upon the floor to prevent overheating or scorching. This operation of turning the grain has been heretofore usually done by hand with a shovel or similar instrument, the attendant walking in the grain for the purpose.

20 The object of my invention is to produce a device by means of which the grain may be turned by revolving paddles or blades caused automatically to traverse the floor of the kiln from end to end thereof, the invention being 25 fully described hereinbelow, and more particularly pointed out in the claims.

Referring to the drawings, Figure 1 is a plan 30 of my improved device for turning malt, parts being broken away and omitted and other parts shown in two positions by full and dotted lines, the half of the wall nearest the observer being horizontally sectioned, as upon the dotted line z' in Fig. 2, the other half as upon the dotted line x' , and a small portion of the wall 35 at the opening through which the driving-shaft and a part of the belt-shifting device project being sectioned on the dotted line y' ; Fig. 2, a side elevation of the same, parts being broken away, and the walls, shafts, and 40 other parts vertically longitudinally sectioned, as upon the dotted line x in Fig. 1, and seen as indicated by the arrow pointed thereon; Fig. 3, a side elevation of a portion of the carriage, drawn to a larger scale and seen in the 45 direction in which Fig. 2 is seen, the shafts being sectioned as on said dotted line x , the figure being drawn to show the manner of raising or lowering the paddle-shafts, parts being shown in two positions by full and 50 dotted lines, and a portion of one of the wheels and a holder for the carriage being vertically

sectioned on the plane of the tracks; Fig. 4, a plan of a portion of the perforated floor and frame of the kiln, drawn to show the opening through the floor with the cover therefor; Fig. 5, a side elevation of one of the clutch-driving sprockets for the paddle-shafts, the shaft holding said sprocket being sectioned, as on the dotted line y in Fig. 7, the whole viewed as indicated by arrow x' ; Fig. 6, an end view of 60 one of the sliding driving-clutches for the driving-sprockets and a portion of the forked bar operating the same, the shaft and spline being sectioned, as upon said dotted line y , the figure being viewed as indicated by arrow z ; Fig. 7, 65 a side elevation of the clutch and a part of the sprocket, with a part of the shaft and spline for the clutch, viewed as indicated by arrows z' and x' ; Fig. 8, an inside elevation of one 70 of the carriage-trucks, seen in the direction in which Fig. 2 is seen, drawn to show the vertical dovetailed cavity or rest within which the frame of the carriage slides at one end, a part at the sides of the cavity being broken away and vertically sectioned to better show 75 the form thereof; Fig. 9, an outline view of a building containing the malting kilns, furnaces, elevator, &c., drawn to a small scale, showing the general arrangement of the parts; Fig. 10, a side elevation of some of the parts, 80 seen as indicated by arrow y' in Fig. 1, drawn to show the mechanism by means of which the paddle-shafts are stopped rotating while the carriage continues to move along its tracks; Fig. 11, a side elevation of parts of the belt-shifting mechanism and driving-pulleys, seen as indicated by arrow y' in Fig. 1, drawn to 85 show more fully the form and operation of the same, parts being broken away; and Fig. 12, a view of some of the same parts, seen as indicated by arrow z' .

Referring to the parts, A are walls that may be supposed to inclose the drying-kiln for making malt, and O the frame for the operating parts of my improved device for turning the malt, built within said walls.

B is a carriage, composed of numerous parts, caused to move backward and forward over the malt from end to end of the interior of the kiln upon horizontal side tracks or ways C, 100 secured to the frame.

D is a horizontal driving-shaft resting in

bearings in the sides of the frame near one end thereof, said shaft being provided with a system of overhanging belt-pulleys, E.

F are the trucks of the carriage, provided with wheels G to roll upon the lower tracks C.

H is the frame of the carriage, consisting of the vertical side pieces, I, and cross-bar J, joining them, said side pieces having bearings on the respective trucks.

10 K are horizontal paddle-shafts resting in bearings at the lower part of the frame, carrying paddles K', provided with blades b for agitating or turning the grain.

L is a driving-shaft for the paddle-shafts, resting in bearings in the frame, and a are sprockets on the shaft L, which carry chains c, that pass around sprocket-wheels v² on the paddle-shafts to turn the latter in their bearings.

15 20 d and o are differential sprockets upon the shaft L, and f are driving-chains, which pass around said differential sprockets and around sprockets g on the main driving-shaft D, also around idle-wheels e at the other end of the frame.

25 N is a lifting device for raising or lowering the carriage to cause the ends of the paddles to sweep near the floor or more distant therefrom, as may be required, said device consisting of a horizontal shaft, h, resting in bearings in the trucks, slotted arms k, to lift the frame, and operating-lever l, with toothed rack i, pawl and pawl-lever n and p, and other minor parts.

30 35 P are devices for tightening the chains f, each consisting of a movable frame, r, which holds the idlers e, and a screw, s, to press said frame in a direction to strain the chain.

40 45 g' and h' are other idlers for the chains f, the former being held to turn, respectively, upon studs i', rigid with the side pieces, I, of the carriage-frame in the planes of the differential sprockets d, and the latter idlers held on pins n' at the ends of arms p', also pivoted adjustably to said side pieces upon rigid studs v, which hold said idlers in the planes of the respective differential sprockets o. These arms are held in positions of adjustment by set-screws o', on account of which said arms, with 50 55 60 65 70 75 80 85 90 95 100 105 110 115 120 125 130 135 140 145 150 155 160 165 170 175 180 ward, the carriage will be raised or lowered. This lever is provided with some simple device for holding the carriage in positions of vertical adjustment—such, for instance, as a pawl, n , and tooth bar or rack i , with pawl-lever p and actuating spring t' , all of common construction, and for which no novelty is claimed.

The grain from the germinating vats or loft 10 is carried into the kiln by a spout, S , and, falling upon the middle of the floor, is evenly distributed thereover by the carriage with its revolving paddles, above described, the carriage being allowed to run during the inflow 15 of the grain to the kiln. After the malt is sufficiently dried the trap d' in the floor is opened and the malt allowed to fall through, the kiln being cleared for a new charge of sprouted grain. The carriage, with its paddles, is brought into use to clear the floor of the kiln by moving the malt from the ends thereof to the trap, which is done by stopping the rotation of the paddle-shafts at each end of the kiln and allowing the paddles to drag 20 as the carriage moves along. This pushes the malt before the paddles and allows it to drop through the opening as the carriage passes in either direction. The paddle-shafts are stopped rotating by the following means: The sprockets a , for driving said shafts, are fitted to turn 25 loose upon the shaft L , and are each formed with a toothed or clutch face, as shown on Sheets 4 and 5, and corresponding sliding clutches, T , are provided on the shaft L to act 30 with or engage said sprockets, as indicated, said clutches being held to turn with the shaft, but permitted to slide longitudinally thereon along splines u' , rigid with the shaft. The clutches are formed with grooves v' , in which 35 rest the forked ends of a shifting bar, a' , to which is secured a lever, b' . This lever is pivoted at c' to a bracket, d' , pending rigidly from the cross-bar J of the carriage-frame. By 40 moving the lever laterally the clutches will be thrown against the sprockets to lock with them and turn the paddle-shafts, or moved back to clear said sprockets to cause the paddle-shafts to cease rotating, as stated. The attendant, 45 standing upon the upper portion of the frame, operates the levers l and b^2 for the purpose stated. Stopping the rotation of the paddle-shaft when the carriage is at one end of the kiln in such position that the blades of the shaft nearest the end of the kiln shall stand 50 vertical, the malt will be drawn or pushed by the advancing carriage from the end of the kiln to the trap. Rotating the shafts again, thence to the other end of the kiln, and stopping them as before, the malt will be drawn 55 from that end of the kiln to the trap.

It is not intended that all the malt on either side of the trap shall be carried to the latter at a single passage of the carriage, but that a portion shall be taken off the top at each passage thereof, the friction of the shafts K and chains c with other parts being sufficient to hold the paddles firmly enough to move a por-

tion of the malt at each passage of the carriage. By continuing this operation the malt will be thrown down the trap without the attendant 70 stepping upon the floor of the kiln, unless to finally sweep the latter.

The paddles secured to the shafts may be of any form desired and arranged in various ways thereon, according to judgment. As shown, 75 they are inclined to the axis of the shaft and placed in two lines on opposite sides thereof; but they may be placed one in advance of the other if found more effectual, and the paddles may be twisted to the form of steamboat pro- 80 peller-wheels or otherwise, as desired. The hubs holding the blades b of the paddles may be cubical in form, as shown in Fig. 2; but I prefer them cylindrical, as shown in Fig. 1, held to the respective shafts by set-screws, as 85 shown. Regarding the two shafts, the paddles are preferably placed thereon so that the blades shall extend at right angles with each other, as shown, so that only those of one shaft shall dip into the grain at once, for the pur- 90 pose of causing a more even strain upon the carriage and the mechanism driving the same.

The belt-pulleys at E , with the straight and the crossed belts therefor, are quite similar to the corresponding parts of iron-planers and 95 some other machines, and the manner of shifting the belts very much the same.

e^2 and f^2 , Figs. 1, 11, and 12, are two parallel sliding heads, each provided with two tines, g^2 , pointing horizontally in opposite directions, the respective belts passing between said pairs of tines, one belt, for instance, resting upon the tight pulley s' and the other upon the loose pulley r' . h^2 and i^2 are, respectively, two bell-cranks or levers pivoted upon a common pin, k^2 , rigid with the frame, said bell-cranks being, respectively, connected at their free ends with said sliding heads by means of pins l^2 and n^2 entering longitudinal slots therein, as shown. The lever h^2 has a short arm, o^2 , reaching out so as to be encountered by a part, a' , of the advancing carriage, as shown, as the latter arrives at one end of the kiln. Similarly, at the opposite end of the kiln, a short lever, p^2 , is pivoted to the frame O and 105 joined by a connecting-rod, r^2 , to the bell-crank i^2 , said lever being in position to be encountered by the other holder of the truck as the carriage reaches the other end of the kiln. Thus the carriage, upon arriving at either end 110 of the kiln, automatically shifts the belt in a manner to start said carriage back toward the other end of the kiln. The heads e^2 and f^2 are fitted to slide independently in their rests or bearings c^2 , but, normally, are joined by a link, 115 s^2 , attached to the pin l^2 , and a similar pin, t^2 , projecting from the head f^2 , so that both must move together.

Now, supposing the belt-shifting device just described to be in the position shown by full 130 lines in Fig. 1, with the belts on their respective pulleys s' and r' and the carriage moving toward the left, it will be seen that when it encounters the lever p^2 the latter will be forced

to the position shown by dotted lines, causing the other parts of the shifting device to be moved to corresponding positions, serving to shift the belts and reverse the direction of the motion of the driving-shaft and carriage. Upon arriving at the opposite end of the kiln the carriage will encounter the arm o^2 , now occupying the position shown in dotted lines, and move the whole belt-shifting mechanism to the position shown in full lines, as before, causing the carriage to again return. By these means the carriage will reciprocate or move from end to end of the kiln until stopped by the attendant.

15 At times—as, for instance, when the heat is low—the drying grain needs to be turned only occasionally, as once in thirty minutes or an hour. When this is the case, it is necessary for the carriage to move only once the length 20 of the kiln and rest until the grain needs turning again, when it is started back to stop upon reaching the opposite end, as before. To cause the carriage to shift the belts to stop it upon arriving at either end of the kiln, the link s^2 25 is removed by the attendant, allowing the heads e^2 and f^2 to move independently. This being done, the carriage, after being started, will simply run to the end of the kiln and stop by throwing the operating-belt onto the adjacent loose pulley, in which case both belts will 30 be on the loose pulleys and become inoperative. To start the carriage again the attendant must throw the other belt upon the tight pulley, when it will move to the opposite end 35 of the kiln and stop, as before.

The frames r of the tighteners P for the respective chains f are held to the frame O by bolts u^2 passed through slots δ^2 therein, in such a manner that said frames r may be moved 40 horizontally by the screws s , as stated, to take up the slack of the chains, said screws being threaded in the frame O .

In practice these drying-kilns are placed one over the other, as shown at A' in Fig. 9, 45 over suitable furnaces, B' . The raw grain is elevated to the top of the building, and, after being germinated, is carried through a spout, S , into the upper drying-kiln, where part of the drying is done, then dropped into the next 50 kiln below through the trap d' , where the drying process is continued, and thence into the kiln immediately above the furnace, where the drying is completed, the heat communicated to the different kilns increasing as the 55 furnace is approached.

What I claim as my invention is—

1. In a device for turning malt, in combination with tracks or guides, a reciprocating carriage provided with rotating paddle-shafts 60 and a driving-shaft for said paddle-shafts, provided with differential sprockets, a main driving-shaft for the carriage, provided with driving-sprockets, and chains for said differential sprockets and driving-sprockets, substantially 65 as shown.

2. In a device for turning malt, in combina-

tion with rigid tracks C , a reciprocating carriage formed with rolling trucks upon said tracks, said carriage being provided with rotating paddle-shafts and driver therefor, and said trucks being provided with adjustable holders a' , to bear upon said tracks, with means, substantially as shown, to reciprocate said carriage, as specified. 70

3. In a device for turning malt, rigid tracks 75 or guides, reciprocating carriage resting thereon, provided with rotating paddle-shafts and driver therefor, said driver being provided with differential sprockets, a main driving-shaft provided with driving-sprockets, driving-chains upon said driving-sprockets and the differential sprockets, and idlers h' and g' for said driving-chains, in combination with tighteners for said driving-chains, provided with idlers, substantially as shown and de- 80 scribed. 85

4. In a device for turning malt, rigid tracks 90 or guides, a reciprocating carriage held thereby, provided with rotating paddle-shafts and a driver therefor, the latter being provided with differential sprockets, a main driving-shaft provided with driving sprockets, and chains for said differential and driving sprockets, in combination with a lifting device, substantially as shown, to raise or lower said car- 95 riage, as and for the purpose specified. 100

5. In a device for turning malt, rigid tracks, a reciprocating carriage held thereon, rotating paddle-shafts provided with sprockets held by said carriage, a driving-shaft for said paddle-shafts resting upon said carriage and provided with loosely-fitting driving-sprockets, and chains for said driving-sprockets and the sprockets on said paddle-shafts, in combination with means, substantially as shown, to 105 lock said driving-sprockets to the driving-shaft, for the purpose stated.

6. In a device for turning malt, rigid tracks 110 or guides, a reciprocating carriage resting thereon, rotating paddle-shafts held by said carriage, a driving-shaft for said paddle-shafts held by said carriage, said paddle-shaft and driving-shaft being each provided with sprockets, and chains for said sprockets, in combination with means, substantially as shown, to 115 reciprocate said carriage upon the tracks, as described.

7. In a malt-turning device, rigid tracks or guides, reciprocating carriage held thereon, provided with rotating paddle shafts, and a 120 driving-shaft for said paddle-shafts, said driving-shaft being provided with loosely-turning driving-sprockets and sliding clutches therefor, turning with said driving-shaft, in combination with means, substantially as shown, to 125 stop said carriage at either end of its run upon said tracks, as and for the purpose set forth.

DAVID A. WALLACE.
